Donald P. Weiss, Kinnelon, N.J., assignor to Advertising Displays Corporation, Englewood Cliffs, N.J.

Filed Sept. 10, 1975, Ser. No. 611,870

Term of patent 14 years

Int. Cl. D6—06

U.S. Cl. D6—85

FIG. 1

FIG. 2

FIG. 3

FIG. 4

Des. 241,292

Page 2 of 2

FIG. 5

FIG. 1 is a front view of an advertising display easel showing my design, the easel legs being folded;

FIG. 2 is a rear view thereof;

FIG. 3 is a top plan view thereof;

FIG. 4 is a side elevational view thereof showing the easel legs extended; and

FIG. 5 is a bottom plan view thereof showing the easel legs extended.

I claim:

The ornamental design for an advertising display easel, substantially as shown and described.
